(57) **CLAIM**

The ornamental design for a combination toothbrush and toothpaste dispenser, as shown and described.

DESCRIPTION

FIG. 1 is a top, front and right-side perspective view of a combination toothbrush and toothpaste dispenser embodying my new design;

FIG. 2 is a right-side, rear and bottom perspective view thereof;

FIG. 3 is a front elevational view thereof;

FIG. 4 is a rear elevational view thereof;

FIG. 5 is a right-side elevational view, the left-side elevational view being a mirror image thereof;

FIG. 6 is a top plan view thereof;

FIG. 7 is a bottom plan view thereof;

FIG. 8 is a sectional view taken along the line 8-8 in FIG. 6; and,

FIG. 9 is a reduced perspective view of FIG. 1.

The dot-dot-dash broken lines represent boundary that form no part of the claimed design. The broken lines showing of the toothpaste dispenser in FIG. 9 depicts environment that form no part of the claimed design.
